2,606,655

COMMODITY DISPENSING PACKAGE AND WRAPPER THEREFOR

Shy Rosen, New York, N. Y., assignor to Milprint, Inc., Milwaukee, Wis., a corporation of Delaware

Application October 30, 1947, Serial No. 782,995

2 Claims. (Cl. 206—57)

1

My present invention relates in general to improvements in the art of packaging piece meal dispensable commodities, and relates more specifically to an improved mode of wrapping groups of similar articles or objects in a manner whereby successive pieces of each enwrapped batch may be conveniently withdrawn without destroying the general contour of the package.

It has heretofore been customary to pack batches or groups of nested articles such as sanitary napkins and other tissues, in rigid cartons each provided with a slot through which the successive articles could be withdrawn as required, after the dispensing slot had been opened. In some cases these tissues are folded, stacked and nested so that removal of each individual article will eject the edge portion of a succeeding tissue, thereby facilitating withdrawal of the articles in succession; and while this method of packaging in rigid cartons is quite satisfactory, it is rather costly, and is in fact prohibitive for use in small pocket size packs where the cost of the wrapper may actually exceed the value of the commodity itself. Due to the delicate nature of this general class of articles, it is however, necessary to prevent excessive crushing or distortion of the batches by maintaining the general contour of the packages until all of the tissues have been dispensed, and the rather rigid prior but expensive cartons were well adapted to serve this purpose.

It is however an object of the present invention to provide an improved package for confining relatively small groups or batches of nested articles such as tissues, in relatively simple and inexpensive flexible wrappers, and in a manner whereby undesirable marring or creasing of the residual articles is avoided, while still permitting convenient withdrawal of the successive tissues from the pack.

Another object of this invention is to provide an improved commodity dispensing package for a group of relatively frail and delicate articles, wherein the prearranged and nested articles of the enclosed group are retained in neatly arranged condition and are amply protected against undesirable crushing until the last article of the group has been dispensed.

A further object of the invention is to provide a simple and durable flexible wrapper for a multiplicity or stack of articles such as napkins or other tissues, which may be readily manufactured at moderate cost, and which may also be conveniently applied to the commodity to produce an effective enclosure from which the successive articles may be quickly removed at will.

2

Still another object of my present invention is to provide a flexible inexpensive wrapper for a plurality of closely nested relatively flat articles, which is adapted to be applied to a group of such articles to effectively protect the same, while providing an enclosure or package having a dispensing slot bounded by relatively rigid guiding edges for facilitating convenient and systematic withdrawal of the successive confined pieces of commodity.

These and other objects and advantages of the invention will be apparent from the following detailed description.

A clear conception of the several improved features involved in my new package, and of the manner in which several modifications of the improved package may be assembled and utilized, may be had by referring to the drawing accompanying and forming a part of this specification wherein like reference characters designate the same or similar parts in the various views.

Fig. 1 is a diagrammatic perspective view illustrative of the initial steps involved in the production of one type of the present improved wrappers and packages;

Fig. 2 is a slightly enlarged perspective view of a complete package embodying a wrapper produced as depicted in Fig. 1;

Fig. 3 is a further enlarged transverse section taken through the package of Fig. 2 near one end thereof, and showing the dispensing slot opened by removal of the tear strip and also depicting the manner in which the batch of napkins or tissues is nested within the wrapper;

Fig. 4 is another diagrammatic perspective view illustrating the initial steps involved in the production of a modified type of the improved wrappers;

Fig. 5 is a slightly enlarged perspective view of a complete package embodying a wrapper produced as in Fig. 4, showing the article dispensing slot being opened by removal of the tear strip;

Fig. 6 is an additional diagrammatic perspective view depicting the initial steps involved in the production of a further modified type of my improved wrappers; and

Fig. 7 is a somewhat enlarged perspective view of a complete package embodying a modified wrapper produced in accordance with Fig. 6.

Although the invention has been illustrated and described herein as being especially advantageously applicable in the production of packages containing batches of relatively flat folded and stacked tissues or paper napkins, it is not my desire or intent to unnecessarily restrict the

scope or utility of the improvement by virtue of this limited disclosure, since the improved features of the method, wrapper and package may be more generally applied in packing diverse other commodities adapted for piece meal dispensation.

The primary purpose of my present invention is to provide an inexpensive but durable and highly protective wrapper for batches of relatively delicate strips or sheets of material, such as folded napkins or tissues, and in accordance with the improvement I provide a flexible wrapper sheet reenforced at selected areas so as to maintain the original or natural shape of the final package to which the sheet is applied, and also having a removable section cooperable with an article dispensing opening and with the reenforcement so as to facilitate withdrawal of the successive articles without undesirably disrupting the package contour. The flexible wrapper stock employed in the primary wrapping sheet may be either transparent or opaque material adapted to be supplied from rolls in strip or ribbon formation; and the auxiliary reenforcing stock may be somewhat stiffer opaque or transparent material, either adhesively attached to the primary sheets, or loosely coacting therewith at the requisite localities so as to produce the desired results. Each of the composite wrappers produced from the primary and auxiliary stock, is preferably provided with an elongated removable tear strip either formed of the primary stock alone, or of the auxiliary stock alone, or of both primary and auxiliary stock, or as a separate element, adapted to coact with one or more of the reenforcing sheets so as to provide a well defined dispensing slot having relatively rigid opposite edges.

Referring especially to Figs. 1, 2 and 3, the improved wrappers revealed therein may be formed as illustrated diagrammatically in Fig. 1, by simultaneously delivering a band of primary relatively thin but durable stock 10 from a supply roll 11, together with two parallel laterally spaced ribbons of auxiliary and somewhat stiffer sheet material 12 derived from a supply roll 13, in superimposed relation. The advancing stock 10 and material 12 may be adhesively united and severed transversely along lines 14 to produce a succession of completed rectangular wrappers each having an elongated tear strip 15 disposed in the gap between the parallel reenforcing ribbons 12 thereon, and each tear strip 15 being provided with an end tab 16 at one extreme end thereof. The stock 10 may be transparent regenerated cellulose or the like while the material 12 may be heavier paper stock, and either or both of these composite wrapper elements may be printed or otherwise supplied with indicia visible from the outside and designating the origin and nature of the commodity which is to be packed in the wrappers.

After the flexible wrappers have been thus produced, each wrapper may be applied to a group or batch of articles, such as a stack of superimposed folded napkins or tissues 18, by placing each batch upon a stiff rectangular plate of cardboard 19 and by causing the reenforcing ribbons to contact the uppermost tissue 18 while the side and end portions of the wrapper are folded about the group and are adhesively united at the end folds 20 and along the bottom seam 21, to produce a completed package as shown in Fig. 2. The tissues 18 are preferably stacked and nested in a manner whereby the longitudinal edge 22 of the uppermost tissue will be disposed directly beneath the tear strip 15 of the enclos-

ing wrapper which extends centrally across the top of the package; and the successive tissues 18 are also preferably folded and have their adjacent longitudinal edge portions overlapped, so that removal of the uppermost article or tissue will always pull the upper longitudinal edge of the next lower tissue 18 upwardly through the dispensing slot 23, as illustrated in Fig. 3. Each package may be opened to provide an unobstructed elongated dispensing slot 23 such as shown in Fig. 3, by merely grasping the tab 16 of the tear strip 15 and by tearing the strip 15, longitudinally from the package in the manner indicated in Fig. 5.

While the tear strip 15 of Figs. 1 to 3 inclusive, has been formed of primary stock 10 alone, this tear strip may also be formed in various other ways, either separate from or integral with the reinforcing material 12. As shown in Figs. 4 and 5 for example, the tear strips 25 are of a composite nature, and the successive wrappers are formed by simultaneously delivering a band of primary stock 10 from its supply roll 11, and a single ribbon 26 of reenforcing material from an auxiliary supply roll 27, in superimposed relationship, after the ribbon 26 has been provided with parallel longitudinal central lines of perforations 28 by means of perforators 29 so as to form the tear strips 25. The superimposed band 10 and ribbon 26 may be adhesively united in any suitable manner, after which the composite band or ribbon may be severed along lines 14 to produce the successive completed wrappers. As in the previous embodiment of the invention, the tear strip 25 may be provided with an end starting tab 16, and the stock 10 may be either plain or printed, transparent or opaque relatively thin and flexible material, while the reenforcing ribbon 26 may be either plain or printed, opaque or transparent more tenacious and stiffer material.

The completed wrappers produced as shown in Fig. 4, may likewise be applied to individual groups or batches of folded napkins or tissues 18 to produce packages such as shown in Fig. 5, each having a tear strip 25 spanning its upper portion. These modified packages may likewise be opened by ripping the tear strips 25 therefrom as depicted, so as to provide an open central slot 23, and in order to facilitate removal of the first napkin 18 its uppermost edge portion may be spot glued to the underside of the adjacent tear strip 25 so that this edge portion will be lifted upwardly through the adjacent slot 23 as the tear strip 25 is being withdrawn. The modified package of Fig. 5 is also preferably provided with a lower internal cardboard reenforcing plate 19 of approximately the same shape as that of the folded tissues 18.

Although the upper reenforcing and tear strip elements of the embodiments of the invention shown in Figs. 1 to 5 inclusive, have been formed from continuous ribbons of material or stock, such procedure is not essential, and these upper elements may also be produced and applied as illustrated in Figs. 6 and 7. In accordance with this further modification of the invention, pre-formed pads 31 of reenforcing material may be successively deposited upon an advancing band of primary flexible wrapper stock 10, and adhesively united therewith along areas 32. Each of the pads 31 is spanned longitudinally by parallel rows of perforations 28 to provide a removable tear strip 33 having an end tab 16, and the stock ribbon 10 may again be severed transversely

midway between the successive pads 31 along lines 14 to produce the successive completed wrappers. These modified wrappers may also be applied to groups or batches of folded and stacked tissues 18 to provide packages such as shown in Fig. 7, 5 each having a tear strip 33 extending longitudinally across its top, but in the package of Fig. 7 the upper reenforcing plates 31 are disposed externally of the primary wrapper sheet 10, whereas in the packages of Figs. 2 and 5 the upper reenforcing sheets 12, 26 may be located 10 within the main wrapper sheet 10.

In each of the embodiments shown, the present invention obviously provides a simple system for producing abundantly reenforced flexible wrappers adapted to enclose batches of relatively delicate articles such as tissues 18 so as to produce compact packages each having a stiff-sided article dispensing slot 23 and capable of maintaining their original shapes or contours until the last tissue has been dispensed. Each type of the improved package is amply reenforced adjacent to at least one edge of the dispensing slot where the most extreme weakness occurs when the slot-concealing tear strip is removed, and while the bottom plate 19 facilitates neat stacking of the batches of commodity, the use of this plate is not essential in cases where relatively stiff or self-sustaining articles are enclosed within the packages. Diverse types of wrapping and reenforcing materials may be utilized depending upon the specific characteristics of the enwrapped articles, and suitable indicia may be applied to either or all of the composite wrapper elements, but the necessity of providing relatively expensive rigid cartons or boxes is entirely eliminated.

From the foregoing detailed description it should be apparent that my present invention provides an improved, flexible wrapper, and package, which enable groups or batches of relatively frail articles to be protectively concealed and packed, while permitting convenient dispensation or removal of the successive pieces. The improved wrappers may be economically produced by the improved method, and provide neat and compact packs which are adapted to maintain their original shapes in spite of considerable abuse. The tear strips of the improved packages do not separate the wrappers into separate parts as in prior packages having access facilitating tear strips or cords, but my present tear strips merely open the dispensing slots without destroying the rigidity of the packs embodying the flexible wrappers. The improved wrappers while being especially useful for the purpose of enwrapping tissues or the like, may also be advantageously utilized for diverse other purposes, and while these wrappers have proven highly successful and practical in actual use as applied to tissue, they obviously may be applied to batches of other strip or sheet-like commodity. It is also to be noted that a rigid edge along one side of each slot or opening is all that is required in order to maintain the desired shape of the 65

package at the dispensing opening and to facilitate withdrawal of the commodity.

It should be understood that it is not desired to limit this invention to the precise details of construction or use of the flexible wrappers, herein shown and described, for various modifications within the scope of the appended claims may occur to persons skilled in the art; and it is also contemplated that specific descriptive terms used herein be given the broadest possible interpretation consistent with the actual disclosures.

I claim:

1. A commodity package comprising, a stack of flatly folded highly flexible articles having overlapping adjacent edges, a flexible wrapper enclosing the stack and having therein relatively stiff re-enforcing sheets of approximately the same size and shape as that of the articles snugly engaging the bottom and top of the stack, the wrapper and the upper re-enforcing sheet being spanned by a tear strip removable to provide a slot extending entirely across the package and the uppermost article having an upper free edge directly adjacent to and extending along the slot, and said tear strip being cooperable with said upper free edge to pull the same through the slot when the tear strip is removed.

2. A commodity package comprising, a stack of flatly folded highly flexible articles having overlapping adjacent edges, a flexible wrapper enclosing the stack and having therein relatively stiff re-enforcing sheets of approximately the same size and shape as that of the articles snugly engaging the bottom and top of the stack, the wrapper and the upper re-enforcing sheet being spanned by a tear strip removable to provide a slot extending entirely across the package and the uppermost article having an upper free edge directly adjacent to and extending along the slot, and said strip being attached to said upper free edge to pull the same through the slot when said tear strip is removed.
